(57) **CLAIM**

The ornamental design for an outdoor lantern having a hand-painted tinted shade as shown and described.

DESCRIPTION

FIG. 1 is a perspective view of my outdoor lantern having a hand-painted tinted shade showing my new design;

FIG. 2 is a front elevational view;

FIG. 3 is a rear elevational view;

FIG. 4 is a right side elevational view wherein the left side elevational view is a mirror image thereof;

FIG. 5 is a top plan view; and,

FIG. 6 is a bottom view.

The broken lines shown on the drawings are for illustrative purposes only and form no part of the claimed design.
